UNITED STATES PATENT OFFICE

EDWIN H. NEWTON, OF KANSAS CITY, MISSOURI, ASSIGNOR TO NATIONAL PAPER BOX CO., OF KANSAS CITY, MISSOURI, A CORPORATION OF MISSOURI

DISPLAY CARTON

Application filed June 2, 1928. Serial No. 282,389.

My invention relates to boxes and more particularly to devices of that character formed from a single sheet of bendable material, such as paper, the principal objects of the invention being to interlock the bottom with the side members of the box, to interlock an integral cover with the side members, to constitute the cover an integral hinged member for closing the front of the box, to provide a retaining wall for the front opening, and to securely latch the several elements of the box in position for shipping and continued use after receipt.

In ordinary practice boxes of this character, for example, for shipping and delivery of cakes and cookies, are ordinarily relatively loosely assembled by interlocking means such as tabs and slots; and a cover is provided which may be removed for access to contents. The structure lacks rigidity and serviceability for continued convenient use. It is my further purpose to provide a box having an open front and which is relatively rigid and will retain its assembled condition even under comparatively rough handling, in which an integral lid permanently covers a portion of the box and may be tilted to give access to the contents without hazard of loosening or releasing the engaged portions of the box.

In accomplishing these and other objects of the invention I have provided improved details of structure, the preferred forms of which are illustrated in the accompanying drawings, wherein:

Fig. 1 is a perspective view of a box constructed in accordance with my invention, shown in closed position.

Fig. 2 is a view of the box showing the cover in open position.

Fig. 3 is a central longitudinal section of the box in position illustrated in Fig. 2.

Fig. 4 is a detail perspective view of the members of the box in partly assembled position.

Fig. 5 is a plan view of the blank from which the box is formed, illustrating the scoring for bending the several members into position for assembly and the several

slits for disposing the members and for receiving locking tabs.

Referring in detail to the drawings:

The blank 1 comprises a substantially rectangular sheet having an irregular contour producing portions and members later described, and provided with similar integral lateral wings 2 adjacent one end defined therefrom by scorings 3, and adapted for inbending over exterior side portions 4 defined by parallel transverse scorings 5 and 6 and parallel longitudinal scorings 7 and 8, said scorings defining also a bottom 9. The wings 2 may be attached to the side members 4 by suitable means such as glue applied adjacent the edges of the wings. The exterior side portions 4 are provided with pairs 10 of tab-receiving slits and longitudinally extending wings 11 and 12. A rear end wall 13 of the box extends continuously from the bottom 9 and is defined by said transverse score line 5 and a similar parallel transverse score line 14.

The wings 11 and 12 are slit from the end wall as indicated by 15 and 16. When the sides 4 are bent to vertical position on the score lines 7 and 8, the side wings 11 and 12 may be bent inwardly into the same vertical transverse plane to overlap, and a tab 17 on one of the wings, for example 12, may be received in a slot 18 in the opposite wing for locking the side wings in engaged position. The end wall 13 may then be up-bent on the score line 5 to overlie the overlapping transverse vertical side wings 11 and 12.

A rear cover member 19 extends integrally and continuously with the end wall 13 and is provided with similar flaps 20 on its ends defined by score lines 21 whereby when the cover member 19 is bent on the score line 14 that marks it off from the end wall, it rests upon the upper edges of the sides 4, and tabs 22 on the wings may be received in the slits 10 of the exterior side members 4 for latching the cover member 19 to the sides. A front cover member 23 extends integrally and continuously with the cover member 19 and is defined therefrom by scoring 24 which also represents the hinged connection between the front and rear cover members. The front

cover member is adapted to overlie the front portion of the box in assembled position.

The cover member 23 is provided with lateral wings 25 defined by score lines 26 on which the wings are bendable, the edges 27 of the wings being arcuate and extending from adjacent the longitudinal score lines 26 to the lateral extremities of the wings whereby the scoring 24 is limited to the transverse 10 diameter of the cover.

The wings 25 are provided with forwardly extending flaps 28 defined therefrom by scoring 29 and divided from the blank by slits 30, and a front wall cover member 31 extending integrally and continuously with the front cover member 23 is defined therefrom by scoring 32 aligned with and substantially continuous with the scorings 29 that mark off the wing flaps 28 from the cover wings 25.

20 The wing flaps may be folded transversely on the lines 29 to overlap and stand in a transverse vertical plane across the box.

A front wall flap 33 integral with the front wall cover member 31 is defined therefrom by scoring 34 and is adapted for inbending toward the inner face of said front wall member 31 to overlie the wing flaps 28 and is provided with ears 35 receivable through notches 36 in the outer edges of the wing flaps to extend under the inner horizontal edges 37 of the notches to lock the overlapping wing flaps in transverse position.

Returning now to the front portion of the blank, recesses 38 formed in the integral wings and exterior side members 2 and 4 produce similar arcuate edges 39 and 40 of the wings and exterior side members respectively when the wings are folded inwardly over the side members, the forming of the 40 recess producing the forwardly extending ends 41 and 42 of the wings and side members respectively. A forwardly extending low front wall or retaining rail 43 is integral with the bottom 9.

45 Extending forwardly from the side members 4 are wings 44 defined from the side members by scorings 45, the flaps being slit from the wall 43 as indicated by the lines 46 whereby the wings of the side members may 50 be folded inwardly to stand vertically with their ends in spaced position transversely of the box. The front end wall or retaining rail 43 is provided with a flap 47 extending continuously and integrally therewith having 55 tabs 48 which may enter notches 49 in the edges of the wings 44 to lock said wings and secure the front wall in vertical position and firm engagement with the sides.

It is apparent that the arcuate edges 39 and 60 40 of the side members and wings provide a top as well as a front opening into the box, and the arcuate wings 25 of the front cover member 23 which overlie the sides of the box are adapted to cover the recessed front portions of the side walls, and the front opening

produced by the abbreviated character of the front wall of the box.

It is apparent, therefore, that a blank being scored, cut and slit as described may be formed into a box such as illustrated, the 70 wings of the side members reinforcing the sides, the transverse side wings 11 and 12 reinforcing the rear wall and providing additional strength for the spaced sides, and the rear cover member being securely engaged 75 with the sides adjacent the inwardly extending wings 11 and 12 whereby the side members are further fixed and the members of the box are locked against longitudinal displacement. The front cover member may be swung back to lie upon the rear cover member.

The arcuate front portions of the side walls and the abbreviated vertical front wall erected and reenforced as described provide a firm structure so that when the front cover member is lifted and particularly when positioned at rest as in Fig. 2, easy access to the box is provided. The front cover member may be lowered to enclose the front portion of the box and the plurality of thicknesses of 80 material provided in the interlocked members renders the structure stable in closed position and little liable to displacement of interlocking parts or breakage of bent edges when the 85 cover is lifted or lowered.

It is apparent that a carton constructed as described is particularly serviceable for display purposes, since a portion only of the cover is hinged and this portion may be swung back to rest upon the box during a display 90 period or for removing portions of the contents. The construction of the box provides a front opening for extensive display and 95 convenient access when the cover is lifted, while the major portion of the contents is protected by the walls of the body portion and the rear member of the cover.

What I claim and desire to secure by Letters Patent is:

1. In a box formed from a single sheet of 110 material including a bottom member, sides continuous with the bottom member having wings bent over upon themselves, interlocking rear end flaps continuous with the sides, and a rear wall continuous with the bottom member, a cover continuous with said rear wall comprising a rear portion having wings overlying the sides, and including means for locking the rear portion with the sides, and a front portion having a front flap and side flaps overlying the sides and provided with 115 flaps engageable by said front flap.

2. In a display carton formed from a single sheet of material including a body comprising a bottom, sides, overlapping rear end flaps 120 continuous with the sides, and a rear wall continuous with the bottom, a cover continuous with the rear wall comprising a rear portion having wings overlying the sides and latched thereto, and a front portion hinged 125

to the rear portion and provided with side flaps for overlying the sides of the body and a front flap latched to the side flaps and forming a vertical closure for the front end of the 5 box.

3. In a box formed from a single sheet of material including a bottom member, sides continuous with the bottom member, interlocking rear end flaps continuous with the 10 sides, wings on the front ends of the sides, a front flap continuous with the bottom and adapted to be lockingly engaged with said wings, a rear wall continuous with the bottom member, a cover continuous with said rear 15 wall, comprising a rear portion having wings overlying the sides and including means for locking the rear portion with the sides, and a front portion on said cover adapted to overlie the flap and wings on the front end of the 20 bottom.

In testimony whereof I affix my signature.
EDWIN H. NEWTON.
